UNITED STATES PATENT OFFICE.

ANDREW J. SANFORD, OF NEWARK, OHIO, ASSIGNOR TO A. H. HEISEY & CO., OF NEWARK, OHIO, A COPARTNERSHIP.

PROCESS OF MAKING CORD-PASSAGES IN CANDLESTICKS.

1,272,862.

Specification of Letters Patent. Patented July 16, 1918.

Application filed June 24, 1913. Serial No. 775,604.

To all whom it may concern:

Be it known that I, ANDREW J. SANFORD, a citizen of the United States, and resident of Newark, in the county of Licking and State of Ohio, have invented a new and useful Improvement in Processes of Making Cord-Passages in Candlesticks; and I do hereby declare the following to be a full, clear, and exact description thereof.

10 My invention relates to the manufacture of glass articles and is particularly concerned with improved processes and methods of manufacture for the production of glass articles such, for example, as a candlestick having formed therein a longitudinal passage for the reception of electrical conductors and the formation of a lateral passage in the side wall of the candlestick communicating with said longitudinal passage.

15 whereby electrical conductors may be introduced through said lateral passage into and through said longitudinal passage. The objects of the invention are to secure economy of manufacture, reducing the number of operations necessary to produce the article of the kind described and to produce a candlestick which may be employed as the standard of an electric lamp, having an ornamental appearance.

20 In the accompanying drawings which illustrate an embodiment of the apparatus by which the improved process may be carried out, Figure 1 is a longitudinal vertical section through the apparatus on the line 1—1 Fig. 3; Fig. 2 is a view similar to Fig. 1 showing the parts in different operative position; Fig. 3 is a plan view of the apparatus with the top font and plunger mechanism removed; and Fig. 4 is a longitudinal

30 sectional view of the completed article.

Referring to Figs. 1 to 3, inclusive, the mold proper consists preferably of two longitudinal sections 1 and 2 hinged together by a hinge pintle 3 passing through suitable lugs 4 and 5. The opposite sides of the mold sections may be securely fastened together by means of a pintle or pin 6 passing through lugs 7 and 8, thus forming when the mold sections are together the mold

40 cavity proper 9. The mold sections 1 and 2 are supported upon a suitable base or bottom plate 10 which is provided with a cup-shaped recess 11 registering with the lower open end of the mold cavity. The base plate 50 10 may be supported by a standard 12 from

a suitable support 13. Suitably mounted and guided within the base standard 12 and the base plate 10 is a mold closing plunger 14 transversely slotted as at 15 to receive a transversely arranged plunger actuating 60 draw bar 16, said draw bar having therein a cam slot 17 within which projects a pin 18 secured to the stem of the plunger 14. By moving the draw bar to the right, as viewed in Figs. 1 and 2, the plunger 14 may be 65 withdrawn from mold closing position shown in Fig. 1 to the depressed position shown in Fig. 2 for the purpose hereinafter described. Mounted upon the upper ends of the mold sections 1 and 2 is a top font 19 70 which may be also formed in sections similar to the mold sections and secured together in substantially the same way. The sections of the top font are provided with the annular shoulders 20 adapted to engage the annular 75 shoulders 21 at the top of the mold sections whereby the top font and mold sections may be securely fastened together. The top font is provided with a neck opening 22 communicating with the mold cavity. Mounted 80 within the annular recess in the top font is a plunger guide and filling ring 23 within which operates a plunger 24 which may be operated in any desired manner to force the glass into all parts of the mold cavity. 85

In order to form a longitudinal passage within the body of the candlestick while still within the mold and also to extend this passage to the outer surface of the candlestick one of the mold sections, as 2 for example, is 90 provided with a valve plunger 25 slidably mounted as here shown, for example, in the base forming portion of the mold section 2. Said valve plunger is provided with an annular passage 26 which when the plunger 95 is withdrawn somewhat from the mold cavity opens communication between the air inlet pipe 27 and the interior of the mold cavity. To actuate the valve plunger the latter is slotted as at 28 to receive a transversely operating valve actuating draw bar 29 (see Fig. 3), this bar having therein a cam slot 30 engaged by a pin 31 mounted in the slotted end of the valve plunger. The air inlet pipe 27 may be provided with a 100 control cock 27a.

In the operation of the device and with the parts in the position indicated in Fig. 1 the mold cavity 9 is charged with glass and the plunger 24 is brought down to press 110

the glass and spread the same thoroughly into the parts of the mold. The stop plunger 14 is then withdrawn from the bottom of the mold cavity by means of the draw bar 16 and depressed to the bottom of the cup-shaped recess 11 in the base plate 10. The valve plunger 25 is then withdrawn to the position shown in Fig. 2 whereby the necessary blast of air is introduced through 5 the lateral opening 32 formed in the side wall of the candlestick by the valve plunger, said air blast forcing the softer molten glass at the longitudinal center of the candlestick downwardly and into the cavity 11 of the 10 base plate in the form of a bubble 33, thereby forming through the center of the candlestick a passage 34. The mold sections are then opened and the article removed. The surplus glass at either end of the formed 15 article is cracked off and the article finished by polishing or grinding as desired. The mold may be constructed to simultaneously form a threaded boss 35 at the top of the candlestick to which the threaded socket of 20 the electric lamp may be secured.

It will be seen therefore that in the single molding operation the article is shaped laterally, perforated, and immediately thereafter has formed therein the longitudinal 25 passage for the reception of the electric conductors, said passage communicating with the lateral opening formed by the valve plunger 25. By the use of this apparatus, therefore, considerable economy in manufacture is secured and a candlestick produced 30 having the conductor passages formed therein in a manner to permit of ready and convenient insertion of electric conductors and to present an ornamental appearance.

40 While I have herein described the particular embodiment of the invention, it is to be

understood that the same may be altered in details and in the relative arrangement of parts within the scope of the appended claims:

What I claim is:

1. The method of manufacture of glass articles which consists in casting the article in solid form in a mold and simultaneously forming a passage through one side thereof and then continuing said passage by blowing operation longitudinally of the article and out through one end thereof while still in the mold. 45

2. The process of manufacturing a candlestick with a conductor passage therein which consists in casting said candlestick in solid form within a mold and around a blower head projecting into the mold cavity to form a lateral passage through one side of the candlestick and thereafter continuing the passage longitudinally through said candlestick to and through the top thereof by a blast of air from said blower. 55

3. The process of manufacturing candlesticks having conductor passages therein which consists in casting the candlestick in solid form within a mold and around a blower head to form a lateral passage through one side thereof, withdrawing a portion of the mold from the top of the candlestick, then withdrawing said blower head and continuing said passage longitudinally through the candlestick and out through the upper end thereof by a blast of air from said blower head. 60

In testimony whereof I, the said ANDREW J. SANFORD, have hereunto set my hand.

ANDREW J. SANFORD.

Witnesses:

MAX B. NORPEL,
GEORGE A. BLOOD.
